(57) **CLAIM**

The ornamental design for a gripper of a reaching and grasping tool, as shown and described.

DESCRIPTION

FIG. 1 is a rear top perspective view of a first embodiment of a gripper for a reaching and grasping tool;

FIG. 2 is a front bottom perspective view of the gripper for the reaching and grasping tool of FIG. 1;

FIG. 3 is a first side view of the gripper for the reaching and grasping tool of FIG. 1;

FIG. 4 is a second side view of the gripper for the reaching and grasping tool of FIG. 1;

FIG. 5 is a top view of the gripper for the reaching and grasping tool of FIG. 1 in an open position;

FIG. 6 is a bottom view of the gripper for the reaching and grasping tool of FIG. 1 in an open position;

FIG. 7 is a rear top perspective view of the gripper for the reaching and grasping tool of FIG. 1 in a closed position;

FIG. 8 is a front end view of the gripper for the reaching and grasping tool of FIG. 1;

FIG. 9 is a rear top perspective view of a second embodiment of a gripper for a reaching and grasping tool;

FIG. 10 is a front bottom perspective view of the gripper for the reaching and grasping tool of FIG. 9;

FIG. 11 is a first side view of the gripper for the reaching and grasping tool of FIG. 9;

FIG. 12 is a second side view of the gripper for the reaching and grasping tool of FIG. 9;

FIG. 13 is a top view of the gripper for the reaching and grasping tool of FIG. 9 in an open position;

FIG. 14 is a bottom view of the gripper for the reaching and grasping tool of FIG. 9 in an open position;

FIG. 15 is a top view of the gripper for the reaching and grasping tool of FIG. 9 in a closed position; and,

FIG. 16 is a front end view of the gripper for the reaching and grasping tool of FIG. 9.

The broken lines of FIGS. 1–16 illustrate environmental structures and form no part of the claimed design.
